US0D1094721S

(12) **United States Design Patent** (10) **Patent No.:** **US D1,094,721 S**
(45) **Date of Patent:** **** Sep. 23, 2025**

(54) **LASER IRRADIATION DEVICE**

(71) Applicant: **P-TECH CO., LTD.**, Pyeongtaek-si (KR)

(72) Inventor: **Yo Sung Choi**, Pyeongtaek-si (KR)

(73) Assignee: **P-TECH CO., LTD.**, Pyeongtaek-si (KR)

(**) Term: **15 Years**

(21) Appl. No.: **29/913,110**

(22) Filed: **Sep. 27, 2023**

(30) **Foreign Application Priority Data**

Jul. 14, 2023 (KR) 30-2023-0027041

(51) **LOC (15) Cl.** **24-01**

(52) **U.S. Cl.**

USPC **D24/209**; D24/200

(58) **Field of Classification Search**

USPC D24/133, 141, 152, 156, 176, 200, 206, D24/208, 209, 217, 221, 231

(57) **CLAIM**

The ornamental design for a laser irradiation device, as shown and described.

DESCRIPTION

FIG. 1 is a perspective view of a laser irradiation device showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
